INVENTOR

WITNESS:

ATTORNEY

UNITED STATES PATENT OFFICE.

GEORGE T. THOMPSON, OF LAKE CITY, COLORADO.

TENT SUPPORT.

Application filed April 25, 1925. Serial No. 25,876.

This invention relates to tents, and more particularly to a supporting structure therefor, which structure is capable of being knocked down and the parts folded in compact form, and thus require but a minimum of space for storage, particularly about some part of a motor operated vehicle, so that a tent can be conveniently carried when touring.

10 The nature and advantages of the invention will be better understood when the following detailed description is read in connection with the accompanying drawings, the invention residing in the construction, combination and arrangement of parts as claimed.

In the drawings forming part of this application, like numerals of reference indicate similar parts in the several views, and 20 wherein:

Figure 1 is a side elevation of a tent partly broken away, showing how the tent is supported by the structure above referred to,

25 Figure 2 is a sectional view taken on line 2—2 of Figure 1,

Figure 3 is a longitudinal sectional view through the transverse supporting bar which connects the posts of the supporting structure,

30 Figure 4 is a sectional view taken on line 4—4 of Figure 3,

Figure 5 is a perspective view of two sections utilized in the formation of the transverse supporting bar.

35 While I have hereinabove stated that the supporting structure forming the subject matter of the present invention is primarily intended to be used in conjunction with tents, I desire to have it understood that it may 40 be used for various other purposes, the showing of the structure in connection with the tent being merely illustrative of one embodiment of the invention, and that its general use is contemplated by the claim.

45 The structure includes a pair of spaced posts, one of which is clearly shown in Figure 1, including a plurality of telescopic sections indicated at 10, 11 and 12 respectively. Consequently each post can be lengthened or 50 shortened as the occasion may require. The respective sections of each post can be constructed from any suitable material, preferably metal, the lower section 10 being equipped with a base 14. The upper end 55 of the section 12 is threaded, and is re-

ceived by a threaded cap 15 from the center of which rises a pin 16 for a purpose to be presently described.

The two posts are adapted to be arranged any distance apart, and connected by a 60 transverse supporting bar made up of a plurality of detachably connected sections 17 and 18 respectively. There are two of the sections 18 used in the formation of this transverse bar, these sections constituting 65 the end sections, while any number of sections 17 can be used, depending of course upon the desired length of the transverse bar. Each of the various sections is of substantially U-shaped formation in cross section, the sections 17 fitting within the sections 18 as shown in Figure 3. The sections 18 are provided with transverse pins 19 to be received by the slot 20 formed in the inner adjacent section 17, each of the latter mentioned sections being provided with said slots 20 adjacent each end, whereby the adjacent outer sections of the bar which are arranged in end to end relation are connected by the sections 17, the latter sections 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

structure can be knocked down or collapsed to produce a comparatively small bundle, which will require but a minimum of space for storage irrespective of where the article is placed. It can be conveniently carried on the running board or in the tonneau of a vehicle by tourists.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

What I claim is:

A supporting bar comprising outer sections arranged in end to end relation and of substantially U-shaped formation in cross section, an inner section adapted to be arranged within the outer sections and bridging the meeting ends thereof, said inner section having slots adjacent the ends thereof, and pins carried by the outer sections and adapted to be received by said slots whereby said sections are detachably connected together. 20 25

In testimony whereof I affix my signature.

GEORGE T. THOMPSON.
